UNITED STATES PATENT OFFICE.

THOMAS J. FEGLEY AND GEORGE O. LEOPOLD, OF PHILADELPHIA, PENNSYLVANIA,
ASSIGNORS TO NORTH BRO'S. M'F'G. CO., OF PHILADELPHIA, PENNSYLVANIA, A
CORPORATION OF PENNSYLVANIA,

RATCHET MECHANISM.

Application filed March 6, 1923. Serial No. 623,163.

To all whom it may concern:

Be it known that we, THOMAS J. FEGLEY and GEORGE O. LEOPOLD, citizens of the United States, residing in Philadelphia, Pennsylvania, have invented certain Improvements in Ratchet Mechanism, of which the following is a specification.

Our invention relates to certain improvements in the construction of ratchet mechanism that is used particularly in hand tools, such as braces; screw drivers; drills, &c. The present invention is especially adapted for hand braces.

The object of the invention is to strengthen and to simplify the construction of the ratchet mechanism, and also to design it so that the pawls can be shifted readily to change the direction of movement of the tool mounted in the brace.

20 In the accompanying drawings:

Fig. 1 is a perspective view of a portion of a brace illustrating our invention;

25 Fig. 2 is a vertical sectional view through the portion of the brace enclosing the ratchet mechanism;

Fig. 3 is a sectional view on the line 3—3, Fig. 2;

Fig. 4 is a sectional view on the line 4—4, Fig. 3; and

30 Figs. 5, 6, 7 and 8 are views illustrating details of the invention.

Referring to the drawings, 1 is the lower member of an ordinary hand brace. This member extends into an opening in a projection 2 of a head 3, which encloses the ratchet mechanism, and is secured to the projection by a transverse pin 4. The head 3 has a threaded extension 5 at the upper end to receive the threaded cap 6. The head also has a threaded extension 7 at the lower end to receive the threaded portion of a sleeve 8, in which is located the body portion 9 of a chuck that holds the tool.

45 Located in the head 3 is a spindle 10, which has a series of ratchet teeth 11 formed as shown in Fig. 3. The reduced lower end 12 of the spindle 10 is secured to the body portion 9 of the chuck by a pin 13. The spindle 10 has a groove 14 into which extends a key 15. This key locks the spindle in the head and is held in place by the sleeve 8, as shown in Fig. 2. The spindle is held between the key 15 and the cap 6.

The head 3 is slotted at 16 to receive the

pawls 17 and 18, Fig. 5. The slot has lateral extensions to receive the pivot members 19 and 20 of the said pawls. The pawls are made in the manner clearly shown in Fig. 5, so that the parts of the pawl that engage the ratchet teeth 11 will be opposite each other. 55

21 designates a shifter made of spring metal and bent at each end, as shown in Figs. 2 and 6. The ends rest upon the pawls and there is sufficient clearance under the shifter to allow either pawl to be tilted clear 60 of the ratchet teeth when the shifter is moved into either extreme position. On the shifter is a pin 22, which extends into an opening in a shifter bar 23, adapted to slide in the projection 2 of the head 3. This bar 70 has three notches 24 arranged so as to receive the plunger 25 that is located in the end of the member 1, as shown in Fig. 3. Back of this plunger is a spring 26, which tends to project the plunger and to keep it 75 in yielding contact with the shifter bar.

In the present instance, the outer end of the plunger is tapered and the notches are shaped so that, with force, the bar can be shifted into any one of the three positions. 80 The central position is neutral, both pawls being locked to the spindle. When the pin is in the upper notch, the bar is in the right hand position, and, when in the lower notch, it is in the left hand position. The ends of 85 the shifter bar project sufficiently to allow the bar to be moved into any one of the three positions.

In order to make any repairs, all that is necessary is to detach the sleeve 8 and to remove the key 15. This allows the spindle to be withdrawn from the head. The cap 6 can be removed and the shifter and pawls can be withdrawn. The parts can be readily assembled. 95

We claim:

1. The combination in ratchet mechanism, of a head; a spindle located in the head and having ratchet teeth in its periphery; a key engaging the spindle and acting to retain 100 said spindle in the head; two pawls at the side of the spindle shaped to engage the ratchet teeth; a yielding shifter bearing upon the pawls; and a shifter rod arranged parallel with the spindle and adapted to 105 bearings in the head, said shifter bar being connected to the shifter.
2. The combination in ratchet mechanism,

of a head; said head having a screw thread at each end and a lateral extension; a spindle having ratchet teeth located in the head; a threaded sleeve at one end of the head; a threaded cap at the opposite end thereof; means for holding the spindle in the head; pawls arranged to engage the ratchet teeth; a shifter for said pawls; and a shifter bar mounted in the extension of the head and connected to the shifter.

3. The combination in ratchet mechanism, of a head having a lateral extension; a spindle mounted in the head, said spindle having ratchet teeth and also having a reduced end; a body portion; a pin securing the said body portion to the reduced end of the spindle; a key holding the spindle in the head; a sleeve secured to the head and enclosing the pin and the key; pawls arranged to engage the ratchet teeth of the spindle; and means for shifting the pawls.

4. The combination in ratchet mechanism, of a head having a lateral extension; a spindle located in the head and having ratchet teeth on its periphery, the head being threaded at each end; a cap mounted on one of the threaded ends to prevent the longitudinal movement of the spindle in one direction; a sleeve mounted on the other threaded end of the head; a key in the head,

which prevents the spindle moving in the opposite direction, said sleeve holding the key in position, the head being recessed at the side of the spindle; two pawls located in the recess and arranged to engage the ratchet teeth of the spindle; a spring shifter for the pawls; a shifter bar located in the extension of the head and connected to the spring shifter; and means for holding the shifter bar in the position in which it is adjusted.

5. The combination in ratchet mechanism, of a head having a lateral extension; a cap secured to one end of the head; a sleeve secured to the opposite end of the head; a spindle located in the head, said spindle having a series of ratchet teeth, one end of the spindle being reduced; a body portion secured to the reduced portion of the spindle and extending into the sleeve; a key securing the spindle in position; pawls pivotally mounted in the head; a spring shifter resting on the pawls; a pin extending from the shifter; a bar having an opening for the shifter pin, said bar having a series of notches; and a spring-pressed plunger arranged to enter any one of the notches as the bar is shifted.

THOMAS J. FEGLEY.
